UNITED STATES PATENT OFFICE.

WILLIAM F. BATHO, OF CHICAGO, ILLINOIS, ASSIGNOR TO ENTERPRISE RAILWAY EQUIPMENT COMPANY, OF CHICAGO, ILLINOIS.

CAR.

1,342,085.

Specification of Letters Patent.

Patented June 1, 1920.

Application filed July 3, 1919. Serial No. 308,636.

To all whom it may concern:

Be it known that I, WILLIAM F. BATHO, a citizen of United States, residing at Chicago, in the county of Cook and State of Illinois, have invented a certain new and useful Improvement in Cars, of which the following is a full, clear, concise, and exact description, reference being had to the accompanying drawings, forming a part of this specification.

10 My invention relates to improvements in cars.

One object of my invention is to provide a hopper for grain cars and the like adapted 15 for the ready discharge of cargo. Another object is to provide a hopper door of a simple and efficient type and provided with safe door operating means. Other objects will appear from the description of the invention hereinafter following.

20 In the drawings forming a part of this specification Figure 1 is a cross section of a portion of a car showing a structure illustrating my invention attached thereto. Fig. 2 is a side elevation of a hopper of said car. Fig. 3 is a cross section on line 3—3 of Fig. 1 with the hopper door and certain parts associated therewith in plan view.

25 Referring to the drawings, the numeral 10 indicates the center sills of a car; 11 a side sill adapted to support the superstructure of the car not shown, as will be readily understood and to which the hopper sheets are secured. An outer inwardly and down- 30 wardly inclined hopper sheet is indicated by the numeral 12 and an inner outwardly and downwardly inclined hopper sheet is indicated by the numeral 13. It will be understood that associated with these hopper 35 sheets are the end hopper sheets 14 and 15 indicated by the dotted lines in Fig. 2 of the drawings which, together with the side hopper sheets mentioned, form a hopper in the bottom of the car body. In practice, a 40 plurality of these hoppers would be employed, preferably arranged in pairs oppositely disposed with reference to the center sills of the car.

45 In continuing the description of one hopper, it will be observed that the said side and end hopper sheets form at the bottom a rectangular opening, preferably substantially square and that thus commercial flat plates may be employed in making the 50 hopper structure thus far described. To the

bottom of the hopper a chute 16 is attached, said chute conforming at its top to the bottom of the hopper sheets 12—15, inclusive, and being therefore preferably substantially square. At its lower end 17 the chute is of 60 a general circular shape. The chute 16 is preferably a hollow casting and in the illustration of my invention appearing in the drawing, has its outer wall 18 substantially parallel with the outer hopper sheet 12 and 65 its inner wall 19 substantially at right angles to the inner hopper sheet 13, thus turning the lower opening of the chute inwardly, with reference to the car. The chute at its upper end is provided with suitable flanges 70 20 by means of which it is securely attached to the lower ends of the hopper sheets by rivets 21. The open lower end of the chute 18 is adapted to be closed by a chute door 22 which is preferably of circular shape and 75 conforms to the opening in which it is mounted, said door being pivoted within the chute preferably by means of a shaft 23 passing through the opening 24 provided in said door and extending at its ends through 80 the walls of the chute. The said shaft is suitably fixed within the door so as to require the swinging of the door on turning of the shaft, the shaft being associated with operating means hereinafter described. 85

90 The interior of the chute is interiorly provided on one side, as for instance the upper side, with a shoulder 25 against which the edge of the door is adapted to jam, to limit its outward swinging movement upon one 95 side of the shaft and is also interiorly provided on the opposite side with a shoulder or lug 26 against which the adjacent edge of the door is adapted to jam to limit the inward swinging movement of the door upon 100 this side of the shaft. The side shoulders are indicated by the dotted lines 27 in Fig. 3 of the drawings and are adapted, together with the proper fitting of the door within the chute, to form a tight closure for the 105 opening thereof.

110 The operating mechanism for the chute door comprises a lever 28 pivoted to the car, preferably by means of the pin 29 engaging the inner end 30 of said lever to the bracket 31 which is secured as for instance, by the rivets 32, to the outer hopper sheet 12. It further comprises a link 33 pivoted to the lever intermediate its ends by a pin 34 and pivotally secured at its other end by the pin

36 to the crank 35 which is attached to the shaft 23. In Fig. 1 of the drawings a further hopper 37 is partially shown on the opposite side of 5 the car from that of the hopper hereinbefore described, and of the same construction. To the crank 38, secured to the door shaft 39, a link 40 is attached by means of a pivotal connection, the said link 40 at its other end 10 being pivotally connected to the link 33 through the pin 36, thus transmitting any motion imparted to one door through the operating mechanism to the other door as well. The link 40 is provided with a turn 15 buckle 140 by means of which the said link can be adjusted to a suitable length to cause the simultaneous full closure and opening of the chute doors. It will be understood that the shafts passing through the door 20 may be extended longitudinally of the car to other similar chute doors thereon, so that if desired all chute doors upon a car, of whatever number, can be operated by a single operating lever. The lever 28 is 25 adapted to be locked to the car by means of a clasp 41 secured to the outer hopper sheet 12, and a pin 42 having a chain 43 attached, thereto, to prevent accidental loss of the pin. The said pin is adapted to hold 30 the lever 28 locked within the clasp. The opening of the chute doors is effected by the removal of the lever 28 from its clasp and the forcing of the same downwardly, thus actuating the link 33 inwardly and 35 through the crank 35 opening one chute door and through the action of the link 40 opening the other chute door, thus permitting the discharge of the cargo through the hopper and the chutes at the bottom thereof. The 40 said lever, links, cranks, and doors, upon full opening of the doors assume the positions indicated by the dotted lines in Fig. 1 of the drawings. To close the chute doors the lever 28 is returned to its locked position 45 within the clasp 41.

I claim:

1. In a car adapted for the carrying of grain and the like, in combination: a pair of oppositely arranged hoppers, chutes 50 extended from said hoppers, a door for each of said chutes, an operating shaft for each of said doors, a crank arm on each of said shafts, an operating lever pivotally connected to the car, a link pivotally connected 55 to said lever and to one of said crank arms, and a further link connecting the two crank arms.

2. In a car adapted for the carrying of grain and the like, in combination: a pair 60 of oppositely disposed hoppers, a rotatable closure member in each of said hoppers, an operating shaft for each of said closure members, a crank arm upon each of said shafts, an operating lever pivotally secured 65 to the car, a link pivotally connected to said

lever and to one of said crank arms, and a further link connecting the crank arms to each other.

3. In a car adapted for the carrying of grain and the like, in combination: a pair 70 of oppositely disposed hoppers, a rotatable closure member in each of said hoppers, an operating shaft for each of said closure members, a crank arm upon each of said shafts, an operating lever pivotally secured to the 75 car, a link pivotally connected to said lever and to one of said crank arms, and a further link connecting the crank arms to each other, said last mentioned link being provided with link adjusting means. 80

4. In a car adapted for the carrying of grain and the like, in combination: a pair 85 of oppositely disposed hoppers, a rotatable closure member in each of said hoppers, an operating shaft for each of said closure members, a crank arm upon each of said shafts, an operating lever pivotally secured to the car, a link pivotally connected to said lever and to one of said crank arms, and a further link connecting the crank arms to 90 each other, said last mentioned link being provided with a turn buckle to adjust its length.

5. In a car adapted for the carrying of grain and the like, in combination: a pair 95 of oppositely disposed hoppers, a rotatable closure member in each of said hoppers, an operating shaft for each of said closure members, a crank arm upon each of said shafts, an operating lever pivotally secured 100 to the car, a link pivotally connected to said lever and to one of said crank arms, and a further link connecting the crank arms to each other, the first mentioned link being pivoted to the lever intermediate the 105 ends of the lever.

6. In a car adapted for the carrying of grain and the like and having hoppers on opposite sides of the center sill, the combination with discharge chutes extended from 110 said hoppers, of doors for said chutes, a lever pivoted to one of said hoppers, a crank arm operatively connected with each door, a link pivotally connected to the lever and to one of said crank arms, an extensible 115 link connecting the crank arms and means for locking said lever when the doors are in closed position.

7. In a car adapted for the carrying of grain and the like, in combination: hoppers 120 on the opposite sides of the center sill, a cast discharge chute for each of said hoppers, a door for each chute and operative means for said doors, each hopper comprising outer, inner and end hopper sheets, 125 forming a rectangular discharge opening, the discharge chute surrounding said opening and having a substantially circular discharge end, the door therein being mounted upon an operating shaft, the operating means 130

for said doors comprising a crank arm for each of said shafts, connections between said crank arms, a lever, and a link connection between said lever and one of said crank

5 arms.

8. In a car adapted for the carrying of grain and the like, in combination: hoppers having chutes arranged in pairs with the discharge openings of the chutes facing each 10 other, doors for the openings of said chutes pivotally mounted on axes extending across the chute openings, and means for operating said doors in opposed pairs simultaneously.

15 9. In a car adapted for the carrying of grain and the like, the combination with a pair of hoppers having discharge openings disposed in alinement and adapted to discharge the grain or other material toward 20 each other, said openings being substantially circular, of pivotally mounted circular doors for said openings, means forming a grain seal between each door and coöperating door frame, and means for simultaneously operating said doors in pairs.

10. In a car adapted for the carrying of grain and the like, in combination: hoppers having chutes arranged in pairs with the discharge openings of the chutes facing toward 30 each other; doors for the openings of said chutes pivotally mounted on axes extending transversely across the centers of the chute openings; and means for operating said doors to swing about their respective axes and thereby permit discharge 35 through said openings.

11. In a car adapted for the carrying of grain and the like, a hopper in the bottom thereof, said hopper being formed by flat

metal sheets convergently inclined and the 40 lower edges of which terminate in a horizontal plane and define a discharge end of non-circular outline, a cast chute having its upper portion of the same non-circular form as said discharge end of the hopper and 45 united thereto so that the chute forms a continuation of the hopper, said chute having a circular lower discharge opening, the plane of which is at an angle to the plane defined by said discharge end of non-circular outline, a closure for said discharge 50 opening of the chute, and means for operating said closure.

12. In a car adapted for the carrying of grain and the like, a hopper in the bottom 55 thereof, said hopper being formed by flat metal sheets convergently inclined and the lower edges of which define a discharge end of non-circular outline, a cast chute having its upper portion of the same non-circular 60 form as said discharge end of the hopper and united thereto so that the chute forms a continuation of the hopper, said chute having a circular lower discharge opening, a closure for said discharge opening of the 65 chute, and means for operating said closure, said closure being pivotally mounted on the chute about an axis extending transversely of the discharge opening thereof and the interior of the chute being provided 70 with stop shoulders to limit the movements of the closure when operated to close the discharge opening.

In witness that I claim the foregoing I have hereunto subscribed my name this 12th 75 day of June, 1919.

WILLIAM F. BATHO.
